UNITED STATES PATENT OFFICE.

BURMAN WISE, OF ORLEANS, NEBRASKA.

STOCK-WATERER.

977,990.

Specification of Letters Patent.

Patented Dec. 6, 1910.

Application filed November 20, 1909. Serial No. 530,640.

To all whom it may concern:

Be it known that I, BURMAN WISE, a citizen of the United States, residing at Orleans, in the county of Harlan and State of Nebraska, have invented certain new and useful Improvements in Stock-Waterers, of which the following is a specification.

This invention has relation to certain new and useful improvements in stock waterers.

10 The aim of my invention is to provide a light, neat, simply constructed and readily operated device by means of which water from a tank can be fed into a trough to maintain the water level at a predetermined 15 height within the trough.

With the above and other objects in view the present invention consists in the combination and arrangement of parts as will be hereinafter more fully described and particularly pointed out in the appended claims, 20 it being understood that changes in the specific structure shown and described may be made within the scope of the claims without departing from the spirit of the invention.

25 In the drawings forming a part of this specification, and in which like numerals of reference indicate similar parts in the several views, Figure 1 is a longitudinal sectional view of a watering trough embodying my 30 invention. Fig. 2 is a top view. Fig. 3 is a large detached detail of the valve disclosing the same in section.

In the accompanying drawings the numeral 5 designates a suitable tank or reservoir 35 to which the watering trough 6 is connected. This trough is of any suitable length, depth and width.

Held within an opening 7 formed in the front 8 of the reservoir 5 is the threaded 40 tube 10, having an integral stop flange 11, held to the inner face of the reservoir. At one end this threaded tube has the hollow semispherical valve casing 12, which is exteriorly threaded as shown at 13. The other 45 end of this tube 10 is threaded, as shown at 14. A suitable packing washer 15 is interposed between the stop flange 11 and the reservoir to insure a watertight connection. Held to the valve casing 12 is a second 50 semispherical valve casing 16, which is also exteriorly threaded as shown at 13, and uniting these two valve casings which form a valve chamber is the threaded collar 18.

The valve casing 16 is provided with the intake opening 20.

55

Held within the valve casing 12 is the elastic valve head 21 having a centrally positioned aperture holding a valve stem 22, which is secured by means of the nut 23. This stem 22 passes entirely through and beyond the tube 10, and at its projecting end carries the nuts 25.

Threading upon the tube 10 is the bracket 26, having the two apertured ears 28 carrying the pin 29, and pivotally held upon the pin 29, by means of an ear 30, which ear is held between the bracket ears 28. This bar is bent approximately at right angles to provide the lower extension 34 and the upper extension 38 provided respectively with 65 the opening 35 and the bolt opening 36, these openings being held at right angles to one another as shown in Fig. 3. Held within the aperture 35 is the stem 22, the nuts 25 being secured on opposite sides of the bar 70 portion 34, while adjustably held within the threaded aperture 36 is the bolt 40 carrying the float 42. This regulator is so arranged that the water level within the trough will be maintained at a short distance above the 75 ears 28 and 30. The float 42 determines the water level within the trough. As soon as the water within the trough is consumed the float 42 will descend to displace the elastic valve head 21 permitting an inrush of 80 water, which as it rises within the trough will again carry the float upward to again close the valve.

The device is simple in construction and positive of operation and the working effects are readily accessible and adjustable.

Having thus described my said invention, what is claimed is:

The herein described water trough, comprising a threaded tube having an integral 95 stop flange and hollow semispherical exteriorly threaded valve casing, a second semispherical valve casing having an intake opening and an exterior screw thread, a threaded collar uniting said valve casing to 100 form a valve chamber, an elastic valve head within said first mentioned casing, a stem adjustably carried by said head, a threaded bracket on said tube having two apertured ears, a pin within said ears, a bar having an 105 extending ear held upon said pin between

the ears of said bracket, said bar being bent approximately at right angles and having an aperture at each end, said stem being held within one of said apertures, means to secure said stem to said bar, a float, and a bolt extending from said float and threading into said remaining bar aperture.

In testimony whereof I affix my signature, in presence of two witnesses.

BURMAN WISE.

Witnesses:

W. P. PIERCE,
JOHN DUNLAY.
